UNITED STATES PATENT OFFICE.

SANFORD I. PEDIGO, OF INDIANAPOLIS, INDIANA. Issued under authority of a patent granted January 7, 1918, for an improvement in **TANK-HOSE CONNECTION.**

1,278,004. Patented Sept. 3, 1918.

Application filed January 7, 1918. Serial No. 210,672.

To all whom it may concern:

Be it known that I, SANFORD I. PEDIGO, a citizen of the United States, residing at Indianapolis, in the county of Marion and State of Indiana, have invented certain new and useful improvements in Tank-Hose Connections, of which the following is a specification.

This invention relates to railway tank hose connections and has as its object to provide a connection so constructed as to strain the water as it issues from the tank of the tender to the locomotive and to provide means whereby the strainer may be freed of sediment and accumulations of solid particles whenever found necessary or desirable.

In the accompanying drawings:

Figure 1 is a view in side elevation of the connection embodying the present invention;

Fig. 2 is a vertical longitudinal sectional view therethrough.

In the drawings, the numeral 1 indicates a railway locomotive tender tank of the ordinary construction and 2 indicates the discharge hose which is connected with the tank through the medium of the connection embodying the present invention, the hose 2 being designed to supply water to the locomotive boiler in the usual manner and being provided with means (not shown) whereby it may be connected with a source of steam supply from the locomotive when it is desired to clean the strainer of the connection.

The connection embodying the present invention comprises tubular sections, one indicated by the numeral 3 and the other by the numeral 4, which sections are connected end to end by means of a union 5, the section 3 being connected at its inner end in any suitable manner with the discharge from the tank 1 and the section 4 at its outer end being provided with a hose connection 6 of any suitable type.

The strainer is indicated in general by the numeral 7 and preferably comprises a foraminous conical body having at its larger end an annular flange 8 which is fitted between the ends of the sections 3 and 4 which are connected by the union 5, the strainer being arranged with its minor end extending in the direction of the outer end of the section 4. Near its forward end the section 3 of the connection is provided with

a downwardly extending branch indicated by the numeral 10 and arranged therein is a cut off valve indicated by the numeral 11. In a like manner the section 4 of the connection is provided with a downwardly extending branch 12 having a cut off valve 13 and by reference to Fig. 2 of the drawings it will be observed that the branch 10 is located rearwardly of the strainer 7 and the branch 12 forwardly of the said strainer. Under ordinary conditions the valves 11 and 13 will remain closed. When it is desired to clean the strainer 7 and remove therefrom any accumulations of solid particles, the hose 2 is connected to a source of steam supply, after which valve 11 is opened allowing steam to pass through the section 4 and through the openings of the strainer, thereby dislodging any accumulations within the strainer, the dislodged accumulations being discharged through the pipe 10. After the strainer has been cleaned the hose is disconnected from the source of steam supply and the valve 11 is closed. The valve 13 may then be opened and water flowing through the strainer will dislodge any solid particles which may have accumulated upon the outer surface of the strainer and these particles will be discharged with the water through the branch 12.

In order that the valves 11 and 13 may be conveniently operated from a point within the locomotive cab, rods 14 and 15 are connected to the handles of the said valves 11 and 13, respectively, and are led into the cab of the locomotive (not shown).

Having thus described the invention, what is claimed as new is:

1. A hose connection of the class described comprising a pipe adapted at its discharge end for the connection thereto of the hose, spaced outlet branches leading downwardly from the pipe, a cut-off valve arranged within each of said branches, the valves being independently operable, and a strainer arranged within the pipe between the said branches whereby one of the branches will be located between the strainer and the discharge end of the pipe and the other branch will be located between the strainer and the inlet end of the pipe.

2. A hose connection of the class described comprising a pipe adapted at its discharge end for the connection thereto of the hose, spaced outlet branches leading downwardly from the pipe, a cut-off valve ar-

ranged within each of said branches, the valves being independently operable, a strainer arranged within the pipe between the said branches whereby one of the 5 branches will be located between the strainer and the discharge end of the pipe and the other branch will be located between the strainer and the inlet end of the pipe, and operating rods connected to the cut-off 10 valves within the pipe branches.

3. A hose connection of the class described comprising a pipe adapted at its

discharge end for the connection thereto of the hose, spaced outlet branches leading downwardly from the pipe, a cut-off valve 15 arranged within each of said branches, the valves being independently operable, the said pipe being formed in sections connected separably to each other at a point between the said branches, and a strainer 20 arranged within the pipe at the point of connection of the said sections thereof.

In testimony whereof I affix my signature.
SANFORD I. PEDIGO. [I. S.]
